UNITED STATES PATENT OFFICE

FREDERICK A. SCHROEDER, OF ROCHELLE PARK, NEW JERSEY, AND HERMAN R. SMITH, OF DOUGLASTON, NEW YORK, ASSIGNEES TO RAYMOND CONCRETE PILE COMPANY, OF NEW YORK, N. Y., A CORPORATION OF NEW JERSEY

APPARATUS FOR DRIVING HOLLOW CYLINDERS

Application filed January 17, 1930. Serial No. 421,372.

This invention pertains to apparatus for driving hollow cylinders used in the building of foundations for buildings, bridges, etc.

For such work hollow metallic cylinders are used in a variety of ways, and the present invention is valuable in connection with any of the methods which call for the driving of the cylinders into the ground.

For the purpose of illustration, however, the operation of the apparatus is illustrated in connection with cylinders sunk in the method known commercially as the Gow system. In that system a comparatively short hollow cylinder is driven into the ground and the space within the cylinder is then excavated in any convenient manner. Then a second cylinder, of slightly smaller diameter, is set concentrically within the first and driven until its upper end is at nearly the same level as the bottom of the first cylinder. The second cylinder is then excavated and a third cylinder, of smaller diameter than the second, is driven, and so on until the desired depth of excavation is reached, generally at bed rock, whereupon the cylinders are filled with concrete to form a column suitable for supporting a superstructure.

The cylinders are of large diameter, and a considerable force is required to drive them. The driving force is all concentrated on the thin rim. When certain kinds of soil are encountered it is difficult to apply sufficient driving effort to the cylinder without cutting or crumpling the rims where the blows of the hammer are applied.

Since the Gow cylinders are of various diameters, it is necessary that the driving mechanism be readily adaptable for those diameters.

It is also necessary to provide the driving means with devices to keep each cylinder properly aligned and concentric with the cylinder that surrounds it.

It has been customary to drive the cylinders with pile drivers of the ordinary type, placing temporary heads or cross bars of various kinds on the cylinders and directing the blows of the pile driver on the center of the temporary head.

A more successful method and apparatus is

that shown in Patent No. 1,787,000, issued December 30, 1930, to F. H. Hunt, in which an adjustable structure is provided to fit the tops of the cylinders and two hammers are used, one at each end of the adjustable structure. Under certain circumstances, however, this apparatus is not satisfactory on account of the time required for making the adjustments, each adjustment requiring the removal and replacing of two or more bolts. This operation is so time-consuming that frequently the operator fails to replace the bolts. This is not a serious matter after the apparatus is in driving position on the cylinder, but it causes considerable trouble if the apparatus touches the cylinder while being lowered into position. When that occurs the anvils are thrown out of adjustment and considerable time is consumed in correcting them.

The principal object of the present invention is to overcome the shortcomings of the above-mentioned devices.

The apparatus herein disclosed provides an adjustable structure settable and lockable by means of a single wrench or handle, and without removable bolts. The diameter of the cylinder to be driven is usually known to the operator before the apparatus is lowered to position, and the anvil structure bears a graduated scale by means of which the required setting may be made. However, it sometimes happens that a cylinder is out of round, in which case the final adjustment must be made while the apparatus is suspended on a cable at the cylinder. The present invention permits that setting to be readily made and locked by one-handed operations of a workman lowered into position on another line.

Further and other objects and advantages will be apparent from the specification and claims, and from the drawings which illustrate what is now considered the preferred embodiment of the invention.

Fig. 1 is a front view of the apparatus in operative position.

Fig. 2 is an end view of the apparatus, on line 2-2 of Fig. 1.

Fig. 3 is an enlarged sectional view, on line 3-3 of Fig. 1.

Fig. 4 is a sectional view, on line 4—4 of Fig. 3.

Fig. 5 is a view, partly in section, on line 5—5 of Fig. 4.

Fig. 6 is a view on line 6—6 of Fig. 1.

Fig. 7 is an exploded view on line 7—7 of Fig. 4.

Fig. 8 is a section on line 8—8 of Fig. 4.

Fig. 9 is a section on line 9—9 of Fig. 5.

Referring to Fig. 1, cylinder 20, fifty-four inches in diameter, has just been driven inside cylinder 22 and the driving apparatus is still in operative position but ready to be withdrawn preparatory to lowering a fifty-two inch cylinder inside cylinder 20, whereupon the driving apparatus will be adjusted for a cylinder of that diameter and lowered to operative position on the new cylinder.

The driving apparatus comprises a hammer 24 guided for vertical movement between I beams 26, tied together at their upper ends by cross channels 28. Cable 30, attached to the top of the hammer by loop 32, serves to manipulate the hammer and, since the hammer is larger than the space between channels 28, the cable is used also to raise and lower the entire apparatus.

Riveted to the lower ends of guides 26 by means of gusset plates 34 are a pair of horizontal channels 36 with their flanges toward each other so as to form a substantially rectangular tubular container or guideway for the two settable driving beams 38 and 40. Channels 36 are bound together on their exteriors by plate 42 across their lower flanges, by plate 44 across their upper flanges, and by steel angles 46 across the tops of the channels. These angles, with their outstanding flanges removed, extend down the sides of channels 36 underneath gussets 34. To complete the filling between gussets and channels, the triangular plates 48 are provided.

Within the channels, at top and bottom, are filler plates 50 and 52 so shaped as to form with the webs of the channels a truly rectangular horizontal supporting guideway for the beams 38 and 40.

Above the guide channels and between the lower ends of vertical guides 26 is a cushion block 54 of wood or other suitable material, held in position by channel 56 and angles 58.

Beams 38 and 40 are similar in shape and are mounted for operation one in each end of the above described horizontal guideway between channels 36. Each beam is provided with wings 60 and 62, projecting from the sides thereof (Fig. 8) and resting on angle guides 64 and 66 welded to the webs of channels 36. The beams are therefore slidably supported by guides 64, 66 and by plate 50.

The beams are provided with extensions 68 and 70 which overlap each other when the beams are set for cylinders of small diameter, and which serve to guide and support the

beams in all their operative positions, as for instance when fully extended as in Fig. 4.

Each beam is provided with a horizontal bore 72 at the open end of which is a threaded nut 74 (Figs. 8 and 9) held by pins 76, through which are threaded screws 78 and 80, screw 78 being left threaded and screw 80 right threaded. The adjacent ends of the screws are coupled by jaw coupling 82, and the screws are supported for rotation by bearings 84 and 86 beside the couplings 82. Fast on screw 78 is a bevel pinion 88; a similar pinion 90 in mesh with pinion 88 is fast on the inner end of stud 92 which is supported for rotation in a bushing 94 fast in the web of one channel 36 and reinforcing plate 96 welded thereto and provided on its outer end with a square portion adapted to receive a handle or wrench. It will be appreciated that when stud 92 is turned by the wrench of the operator, screws 78 and 80 will move beams 38 and 40 simultaneously outwardly or inwardly. Scale 98 on the upper flange of beam 38 aids the operator in setting the beams at predetermined points. A set screw 99 serves as a stop to limit the outward travel of the beams to prevent them becoming disengaged from their screws.

The outer ends of the beams are fitted with detachable hardened jaw pieces 100 held in place in the beams by washers 102 through which pass bolts 104. Thus the jaws may be readily replaced. Each jaw has a downwardly projecting lip 106 which engages the outside of the top of the cylinder, while the downwardly projecting surface 108 (Fig. 9) of the beam engages the inner surface of the cylinder.

It is to be understood that the invention is not limited to the specific embodiment herein illustrated and described but may be used in other ways without departure from its spirit as defined by the claims which follow.

We claim—

1. In apparatus for driving hollow cylinders, in combination, a pair of driving beams, a horizontal guideway for supporting said beams in alignment with each other, the opposite ends of said beams projecting beyond said guideway to engage a cylinder, manually operable means for simultaneously and equally adjusting said beams into and out of said guideway whereby the apparatus may be adapted for driving cylinders of different diameters, members carried by the horizontal guideway, and a force applying means operating within said members for applying a driving force to said guideway and for bodily raising said apparatus.

2. In apparatus for driving hollow cylinders, in combination, a plurality of driving beams having inclined outer ends, jaws in the outer ends of said beams overhanging the inclined surface thereof and cooperating with the inclined surface to provide a cylin-

der wall recess, said beams at their outer ends adapted to have the inclined surfaces engage the inner rim of a cylinder and said jaws adapted to engage the top of a cylinder and overhang the outer rim of said cylinder whereby lateral displacement of the beams is prevented when driving, together with means for adjusting said beams simultaneously and equally to adapt the apparatus for driving cylinders of different diameters.

3. In apparatus for driving cylinders, a support, driving beams laterally adjustable in said support for engaging cylinders of varying diameters, guiding members carried by the support, a force applying element operating within the guiding members to apply a driving force to said support, and means for raising the driving beams out of contact with the cylinder, said means operating through the force applying element.

4. In apparatus for driving cylinders, a support, driving beams laterally adjustable in said support for engaging cylinders of varying diameters, guiding members carried by the support, a force applying element operating within the guiding members to apply a driving force to said support, means connecting the guiding members, and means for operating the force applying element said force applying element coacting with said connecting means to raise the driving beams out of engagement with the cylinder upon raising the force applying element above its normal operating range.

In testimony whereof we hereto affix our signatures.

FREDERICK A. SCHROEDER.
HERMAN R. SMITH.
